SLIVER BALLING MACHINE

Adam Johnston Stalker, Nazirunge, British India, assignor to Textile Appliances Limited, Calcutta, Bengal, British India, a company of India

Application September 30, 1943, Serial No. 504,487
In British India September 30, 1942

16 Claims. (Cl. 19—158)

This invention is for improvements in and relating to roll-forming or balling machines for the sliver of jute, hemp, flax and like materials and relates essentially to such machines in which the roll, ball or disc (hereinafter termed ball) is wound by a frictional drive on the peripheral surface thereof from a driving pressure wheel or roller, the sliver to be balled entering the nip between the peripheral surface of the ball and the said driving pressure-roller. The ball is wound on a balling centre or centres about a stationary axis and the pressure-roller, while maintaining the driving surface thereof in positive driving engagement with the peripheral surface of the ball while the winding is progressing, is capable of movement away from the stationary balling axis in order to accommodate the ever-increasing diameter of the ball. Roll-forming or balling machines of the above-described construction are termed hereinafter and in the appended claims "machines of the kind referred to."

One well-known form of such machines is described in British Patent No. 444,062. The ball is frictionally wound on retractable balling centres about a stationary winding axis by a single gear-toothed or plain positively driven pressure-roller which is mounted on a pivoted arm so as to be free to travel outwards, i. e. away, from the winding axis as the diameter of the ball grows. The ball is wound between side plates which completely enclose the sides of the ball as it is being wound, the said plates being of disc form, being mounted to revolve on ball-bearings concentrically with the balling centres, and being axially retractable with the latter in order to allow the ball, when formed, to drop out of the machine and then to be returned again into their ball-confining positions for the initiation and development of a fresh ball.

According to British Patent No. 505,333 (which is a patent of addition to No. 444,062) the means for retracting the balling centres to allow the ball to drop out of the machine comprises pivoted levers which are operable under the control of cams which positively operate the said levers both into the retracted and the non-retracted positions of the balling centres. The general arrangement described in the two British patents is such that when a ball has been built up to its maximum diameter in the machine, the cam-shaft is rotated to retract the balling centres and the side plates, the ball is dropped out of the machine, the balling centres and side plates are returned again into their closed positions, and the pivotally mounted arm carrying the driving

pressure-roller is automatically swung back to bring the same into engagement with the balling centres for the initiation and development of a fresh ball.

5 In British Patent No. 545,859, there is described a roll-forming or balling machine of the general kind referred to but in which, instead of the ball being built up between large rotatable discs as in British Patent No. 444,062, it is formed between partial side plates which shroud the nip of the driving pressure-roller with the ball and part of the end surface and sides of the ball and the said side plates are mounted to be movable during a part at least of the balling period in order to 10 maintain effective support on the sides of the ball while keeping the nip with the driving pressure-roller shrouded during the whole of the balling period.

In a specific and preferred construction of the 20 said machine of British Patent No. 545,859, the remainder thereof is of the general construction described in British Patents Nos. 444,062 and 505,333, but the two partial side plates are mounted for sliding movement on normally stationary 25 support-and-guide rods and the machine comprises slotted levers carried by the pivoted arm of the driving pressure-roller at each side of the latter, and a stud, pin or the equivalent on each of the said side plates extending into the slot of the corresponding side lever, whereby only when 30 the said side levers have moved with the arm of the driving pressure-roller to an extent sufficient to bring the studs, pins or the equivalent of the side plates at one end of the said slots will the 35 said side plates partake of the movement of the pivoted arm during the remainder of the balling period.

While being easier and cheaper to make than the large rotatable discs of British Patent No. 40 444,062, a disadvantage of the partial side plates as described in British Patent No. 545,859 is that owing to the said side plates not being concentric with the balling axis but moving, during balling, in a direction away therefrom and transversely 45 thereto, means are not provided for relieving the pressure of the partial plates on the sides of the ball when it is desired to discharge a completed or partly-formed ball from the machine. This is a disadvantage which seriously affects the smooth 50 working of the machine and it is a general object of the present invention to overcome the same.

A specific object of the invention is to provide a roll-forming or balling machine of the kind referred to, but having only partial side plates of the general kind indicated in British Patent No.

545,859, wherein the lateral pressure of the said partial side plates on the sides of the ball may be relieved in order to permit a more ready discharge of the ball from the machine, such result being obtained in a particularly simple and advantageous manner.

Another object of the invention is to provide the side plate retraction means aimed at in the immediately preceding paragraph of such a character as to be operable to release the ball from the machine at any stage during balling should it be desired to cut out the partly formed ball and to start afresh.

Yet another object is to provide the said retraction means for the partial side plates in such a form that the side plates derive their movements from the actual support-and-guide means on which they are mounted for longitudinal movement in following up the nip of the ball with the driving pressure-roller.

Another object is to arrange the operation of the retraction means for the partial side plates under the same primary control as the balling centres and, particularly, that such primary control should comprise a system of cams and pivoted levers according to British Patents Nos. 444,062 and 505,333.

A further object of the invention is to provide retraction means for the partial side plates which are under the control of a pivoted lever, which pivoted lever is positively operated in both directions of movement by the aforesaid primary control.

A still further object of the invention is to provide the retraction means for the partial side plates in such a form that, when the balling centres open, the side plates are positively retracted from the sides of the ball under the same control as the balling centres and are positively returned again into their ball-confining positions by the said control.

Yet a further object of the invention is to provide a retraction means for the partial side plates which is adapted to be operated at the same time, and for the side plates to remain open for the same period, as the balling centres.

A still further object of the invention is to provide an alternative embodiment of retraction means whereby the partial side plates may be retracted from their ball-confining positions upon the balling centres being opened, but are closed again before the balling centres by separate means, thereby remaining open for a shorter period than the said balling centres.

Another object of the invention is to provide an improved mounting for the partial side plates which, while being easier and cheaper to make than the slotted link mounting of British Patent No. 545,859, is particularly suitable for permitting the pressure of the side plates on the ball to be relieved according to the previously defined objects.

The invention as to its general features of novelty, advantages and the above and other objects, together with the constructional details of certain preferred embodiments thereof, will now be clearly understood from the following description which is given, by way of example, with reference to the accompanying drawings, while the scope thereof will be more particularly defined in the appended claims. In the said drawings:

Figure 1 illustrates diagrammatically, in partial section, a plan view of a preferred form of roll-forming or balling machine incorporating the improvements according to the invention,

Figure 2 illustrates diagrammatically, in end elevation, also partly in section, and with all other parts omitted, the mode of retraction of the partial side plates according to the improvement incorporated in Fig. 1, the machine being shown empty of a ball.

Figure 3 is a view at 90° of the control-can shown in Figure 2 and illustrates the position of the cam during balling.

Figure 4 illustrates diagrammatically, in side elevation, considerably enlarged and with all other parts omitted, the positions of the side plates on their eccentric guide-and-support rods relatively to the balling centres when the machine is empty, together with the improved side plate retracting means according to Figures 1 and 2.

Figure 5 is a view similar to Figure 4, but without the side plate retracting means, showing the stage during balling when the latter has progressed sufficiently to permit the side plates to partake of the movement with the driving pressure-roller away from the axis of the ball.

Figure 6 is a diagrammatic plan view, in partial section, of a modification of the side plate retracting means as compared to Figures 1 to 4, and

Figure 7 is an end elevation corresponding to Figure 5.

The general construction of a roll-forming or 30 balling machine to which the invention relates is the same as in the previously referred to British Patents Nos. 444,062, 505,333 and 545,859 to which reference may be had for a full and detailed description of the construction and operation of the main parts of the machine.

Briefly, as stated in the said specifications and as shown in Figure 1 of the present drawings, the ball of silver is formed in the machine upon a pair of toothed centres 5 and is driven by a toothed driving pressure-roller 34 initially engaging with the teeth of the centres and thereafter engaging frictionally with the peripheral surface of the ball. The driving pressure-roller is carried on an arm 36 pivotally mounted on a shaft 40, automatic means being provided for initiating the formation of a fresh ball, the said means comprising a device (not shown in the present drawings) for swinging the arm 36 towards the centres 5 so that the driving pressure-roller 34 is brought into mesh with the teeth 46 on the latter.

At the completion of balling, or when it is desired to stop balling at any intermediate stage owing to the ball being faulty or for any other reason, it is necessary for the centres 5 to be retracted from one another in order to free the ball and then to be brought together again to grasp fresh silver for a new ball. To this end, the said centres are retractable by means of rods or levers 47 connected to the ends of levers 6 pivoted about axes in their intermediate parts at 48 as described in British Patent No. 444,062 and the operation takes place entirely automatically at the completion of balling or by a manual control if at an intermediate stage. In the present specification, where explanation is given herein-after referring to operation of the parts "at the completion of balling" it will be understood that this is merely for convenience in description and that the same explanation holds good for operation of the mechanism under the aforesaid manual control at an intermediate stage of balling.

As described in British Patent No. 505,333, the aforesaid retraction and return of the balling centres are controlled by means of ball-release-

control cams 20 mounted on the lay cam-shaft 41 of the machine and which are operable to pivot inwardly the other ends of the levers 6 carrying the cam-engaging rollers 49 in order to retract the balling centres. Such cams are preferably of the kind described with reference to Figure 5 of British Patent No. 505,333 whereby a continuous control of the retracting levers 6 both into the retracted as well as into the non-retracted positions is effected by means of a female cam arrangement provided by the single roller 49 on the end of each retracting lever which engages in a continuous endless groove 20B provided in the surface of the corresponding cam 20.

According to British Patent No. 545,859, the ball is built up on the centres between partial side plates 100 and 100a which shroud substantially only the nip with the driving pressure-roller and part of the end surface and sides of the ball. Each of the said side plates 100, 100a is shown in British Patent as comprising a curved cut-away portion which conforms substantially to the shape of the balling centres 5 and has also forward extensions or projections which are adapted to extend respectively over the top and below the said balling centres and to confine the upper and lower sides of the ball during winding. The area of support on the sides of the ball is therefore not confined only to regions immediately adjacent the nip with the driving pressure-roller, but extends also to other adjacent areas and this permits a tightly wound and firmly supported ball to be built while still retained for the side plates their character of being only partial plates.

The said side plates carry respectively upper and lower lugs or brackets 103, 103a whereby the said side plates are each slidably mounted and glided on upper and lower guide rods or the equivalent members 104, 104a respectively, the forward ends of which guide rods are journaled in the front of the machine frame as shown in Figure 1 of the present specification, while their rear ends are journaled in and extend through the rear of the machine frame.

According to British Patent No. 545,859, and/or in accordance with other and improved means as will be described more particularly hereinafter and which form one feature of the present invention, each of the said side plates 100 and 100a is furthermore provided with connection means to the corresponding side of the mounting carried by the pivoted arm 36 on which rotates the driving pressure-roller 34, and the arrangement is such that, during balling, and after remaining stationary for an initial short period, the side plates follow up the nip of the ball with the driving pressure-roller and finish up in new limit positions at the completion of balling as clearly described and shown in British Patent No. 545,859, from which new limit positions they are thereafter returned into their original positions for the initiation and development of a fresh ball.

In the improved form of machine in accordance with the present invention, however, as shown in Figures 1 to 4, the two pairs of guide rods 104, 104a are eccentrically mounted and journaled in the machine frame and, where they extend through the rear of the said frame, they each carry a sprocket wheel 120, 120a.

That one of the ball-release-control levers 6 which is on the left of the machine looking at the latter from the front in the direction of the

narrow of Figure 1, is extended beyond the roller 49 at 121 and the end of the said extension projects through the apertured end of a further lever 122 which is mounted to extend in a substantially vertical plane at the back of the machine frame and is pivotally mounted on the latter intermediate its ends at 123. To the two ends of the said pivoted lever 122 are connected, as shown more particularly in Figure 2, the two ends of a chain 124 which passes round the four sprocket wheels 120, 120a in the direction shown in this figure, so that all the four sprocket wheels are connected to one another in series and whichever way the chain is pulled the two sprocket wheels 120 rotate in one direction, i. e. clockwise or anti-clockwise, and the two other sprocket wheels 120a rotate in the opposite direction, i. e. anti-clockwise or clockwise.

As shown in the figures, the continuous endless groove 20B in each of the ball-release-control cams 20 has a relatively sharply-varied operating part 20C which extends approximately for only about one third of the said groove. During balling, when the pivoted ball-release levers 6 are in their unoperated positions corresponding to a substantially closed position of the centres, the cam-engaging rollers 49 on the ends of the said levers are each in a position at substantially the middle of the said operating part 20C of the camming grooves 20B as shown in Figures 1 and 3, Figure 3 being a view at 90° of the cam 20 shown in Figure 2.

The operation of the arrangement is as follows: At the completion of balling, when the partial side plates have reached their new limit positions aforesaid, the lay cam-shaft 41 is operated in the manner described in British Patent No. 505,333 and the cams 20 rotate in the direction of the arrows shown in Figures 1 to 4 of the present drawings, thereby pivoting inwardly the corresponding ends of the levers 6 and pivoting outwardly the other ends of the said levers to which are connected the levers 47 and thereby retracting the balling centres 5 into their ball-release positions. At the same time, the said rotation of that one of the cams 20 on the lay-shaft 41 which corresponds to the ball-release lever 6 having the extension 121, causes the said extension to pivot inwardly of the machine with the corresponding end of the lever 6. It thereby arrives into the dotted position shown more particularly in Figure 2 and carries with it the upper end of the pivoted side-plate operating lever 122 which pivots about its mounting 123. The said inward pivoting of the upper end of the lever 122 slackens the chain 124 at the top, but causes an outward pivoting of the lower end of the said lever into the position shown in dotted lines, which thereby pulls on the chain 124 in the direction of the arrow shown at the bottom end of the said lever. This causes a rotation of the four sprocket wheels in the directions of the arrows shown, the two sprocket wheels 120 of the side plate 100 rotating in an anti-clockwise direction and the two sprocket wheels 120a of the side plate 100a rotating in a clockwise direction. Since the sprocket wheels are mounted on the corresponding guide-and-support rods 104, 104a of the side plates and the said guide rods are eccentrically mounted in the machine frame, this causes a movement of the two pairs of guide-and-support rods in opposite directions away from one another and the side plates 100, 100a are thereby retracted from one another, both moving from the positions shown in full lines in Figure 2 to

the positions shown in dotted lines. The latter positions are their ball-non-confining positions in which the lateral pressure which they had been exerting on the sides of the ball is removed and the latter is free to be discharged from the machine.

The amount of retraction of the partial side plates 100, 100a which is necessary completely to free the ball for discharge from the machine need only be small, just sufficient to relieve the pressure on the sides of the ball, and it has been found that a movement of the order of only about one quarter of an inch of each side plate may be sufficient.

While the said retraction is taking place, the continued rotation of the cams 20 retains both the side plates and the balling centres open for approximately two thirds of the revolution of the cams, until the other end of the operating part 20C of the groove 20B reaches the camming rollers 49. The ends of the levers 6 which carry these rollers then start to pivot outwardly again, thereby returning inwardly the other ends thereof of carrying the levers 47 and closing the balling centres 5 again. The balling centres then grip the fresh sliver which is being fed into the machine and the new ball is initiated. At the same time as the balling centres close, the extension 121 on the corresponding ball-release lever 6 also moves outwardly with the cam-operated end of the said lever and returns into the position shown in full lines in Figure 2. This pulls on the upper end of the chain 124 and all the sprocket wheels 120, 120a rotate in the opposite directions to their previous rotation, namely the sprocket wheels 120 rotate clockwise and the sprocket wheels 120a anti-clockwise in order to restore the guide rods 104, 104a and the side plates 100, 100a to their original ball-confining positions ready to exert lateral pressure on the fresh ball being initiated.

The partial side plates 100, 100a are furthermore returned into their correct longitudinal positions on the guide rods 104, 104a (which positions correspond to the nip of the fresh ball being initiated and are shown more particularly in Figure 4) by being pushed back thereto by the return swing of the pivoted driving pressure-roller arm 36 operating on the previously referred to connection means between the said side plates and the said arm, an improved form of which connection means (as compared to the pin and slot and lever assembly of British Patent No. 545,859) will be described more particularly hereinafter. In actual practice, the lateral return of the retracted side plates into their ball-confining positions by the return eccentric rotation of the aforesaid guide-and-support rods 104, 104a is effected at the same time as the said side plates are being restored into their correct longitudinal positions on the guide rods by the return swing of the driving pressure-roller arm 36.

It will be seen that in the embodiment of the invention illustrated in Figures 1 to 4, the retraction from and return of the partial side plates 100, 100a into their ball-confining positions are effected positively in each direction by the pivotal movement of the side plate operating lever 122 about its mounting 123. Furthermore, the movement is controlled by an extension on one of the ball-release levers 6 which controls the opening and closing of the balling centres 5 so that it takes place from the same point in the rotation of the controlling cam 20 and the opening and closing of the side plates is for the same duration as for the balling centres.

Figures 6 and 7, however, illustrate a further embodiment of the invention which is substantially similar to the embodiment of Figures 1 to 4, but in which the side plate operating lever only rotates the sprocket wheels of the side plates in one direction of movement and furthermore the duration of opening of the side plates is less than that of the balling centres.

As shown in Figures 6 and 7, the side plate operating lever 122 is now pivoted at 123 to the outside of the machine frame immediately below one of the ball-release-control cams 20 and carries, intermediate its ends, a further stud or roller 125 which is also engaged in the groove 20B of the cam but on the underside of the latter, namely at 180° to the ball-release-control roller 49 and with the said groove shaped as shown in Figure 7. The front end of the said lever 122 extends through a slot 126 in a bracket 127 bolted to the machine frame. The said front end of the lever 122 has attached thereto one end of the chain 124, which passes around the sprocket wheels 120 and 120a on the eccentric guide-and-support rods 104, 104a in the same direction as in Figures 1 to 4 and is secured at the other end to an uncut section of teeth 127 on the last sprocket wheel 120 in the series. To that guide rod 104 on which is mounted the said last sprocket wheel in the series is secured an automatically operating restoring means, such as a counterweight 128, spring or the equivalent, which yieldingly opposes any tendency of the chain 124 to rotate the sprocket wheels from the normal positions shown in full lines and which correspond to the ball-confining positions of the side plates.

As in the case of Figures 1 to 4, the ball-release-control roller 49 is normally, during the whole of the balling period, in the middle of the sharply varied operating part 20C of the cam-groove 20B, but the side plate controlling roller 125 is now substantially in the middle of the remaining straight part of the groove 20B.

The operation of the arrangement is as follows: At the completion of balling, and when the partial side plates have moved into their new limit positions in following up the nip of the ball with the driving pressure roller 34, the cam-shaft 41 operates by the cams 20 in the manner previously referred to on the ends of the ball-release-control levers 6 which carry the cam-engaging rollers 49. The rotation of the said shaft and cams is in the direction of the arrow shown in Figure 7 and the same as in Figures 1 to 4. The balling centres immediately open but, since the side plate controlling roller 125 still travels for about one-half the distance of the straight part of the groove 20B outside the camming part 20C of the cam 20, the side plate control mechanism is not immediately operated. Eventually, however, that end of the part 20C of the camming groove 20B which is approaching the roller 125 reaches the said roller and moves the same, carrying with it the front end of the side plate operating lever 122 into the said part 20C of the camming groove. This causes the front end of the said lever to move outwardly from the position shown in full lines at one end of the guide slot 126 of the bracket 127 into the position shown in dotted lines at the other end of the said guide slot (Figure 6). This movement pulls on the corresponding end of the chain 124, thereby causing a rotation of the sets of sprocket wheels 120, 120a and of the eccentric guide rods 104, 104a on which they are mounted, in the respective (opposite) directions shown by the arrows

in Figure 7, and against the action of the counterweight 128. This causes the two side plates 100, 100a to be retracted from their ball-confining positions (shown in full lines) into the positions shown in dotted lines where the lateral pressure which they had been exerting on the sides of the ball is removed and the latter is free to be discharged from the machine.

The continued rotation of the cam 20 first causes thereafter the side plate control roller 125 to return into its normal position in the straight part of the camming groove 20B, before the part 20C of the said groove operates again on the ball-release-control roller 49 to return the balling centres into their sliver-gripping or balling positions. As the said side plate control roller is returned by the camming groove into its normal position, it returns the front end of the side plate operating lever 122 into its normal position shown in full lines in Figure 6. As distinct from the arrangement in Figures 1 to 4, however, this positive return of the side plate operating lever 122 into its full-line position does not positively return the sprocket wheels 120, 120a also. This is effected by the slack (which the return of the said lever into its normal position thereby causes in the chain 124) being automatically taken up by the counterweight 128 which tends to effect a return rotation of the guide rod 104 on which it is mounted. The sprocket wheels 120, 120a are thereby rotated in the reverse directions to the arrows, back into their original positions. This causes a corresponding rotation of all the eccentrically mounted guide rods 104, 104a on which the said sprocket wheels are mounted, with a corresponding return of the side plates 100, 100a into their ball-confining-positions ready to exert lateral pressure on the fresh ball which is being initiated and built up.

After this, as the cams 20 complete their one revolution and the rollers 49 on the ends of the levers 6 resume their positions in substantially the middle of the part 20C of the camming grooves, the corresponding ends of the said levers 6 are pivoted outwardly again, with a corresponding inward movement of their other ends and the balling centres are returned into their balling positions.

It will be seen that, whereas in Figures 1 to 4 both the balling centres and the partial side plates remain completely retracted during that part of the revolution of the cams 20 which corresponds to the straight part of the camming groove 20B which is outside the part 20C, and which is for about two-thirds of the revolution of the cams, the modification of Figures 6 and 7 results in the balling centres also remaining open for about the same period but the side plates only remain retracted for about one-half of this period, namely for about one-third of the complete revolution of the cams. Whereas both arrangements are convenient, that of Figures 1 to 4 is preferred because in Figures 6 and 7 the side plates tend to close rather quickly and, if too quick, are apt to catch the ball again before it has completely discharged. On the other hand, it may sometimes be more convenient on an existing machine to install the arrangement of Figures 6 and 7 rather than that of Figures 1 to 4.

Generally speaking, however, both forms of the invention are particularly suited for application to existing machines with the minimum of inconvenience and alteration in standard design. In most standard machines of the kind

made according to British Patent No. 545,859, the ball-release-control levers 6 engage with their camming rollers 49 over the top of the cams 20 as shown for the right-hand lever 6 in Figure 1 looking in the direction of the arrow. In order to make the minimum alteration, the modification of the left-hand lever 6 for operation of the side plate lever 122 is shown with the said lever 6 altered to extend below the cam 20 and not above it. It will be understood, however, that this is not necessary and in manufacturing new constructions of machines incorporating the improvements according to the invention, the ball-release-control levers 6 may be mounted to extend either both above or both below the corresponding cams 20 and the side plate retracting levers may be designed to act accordingly.

An important advantage of a roll-forming or balling machine incorporating the improvements according to the invention is that a ball (completed or otherwise) may be discharged from the machine in a comparatively short space of time, thereby reducing to a minimum the dwell or non-winding period during which the machine is not winding even though sliver is being delivered thereto from the carding machine at a constant rate of speed. During this dwell, sliver passes into the machine and is usually wound on the ball as a double end which may result in a considerable variation in the thickness of the yarn into which the sliver is ultimately made. In machines of the kind described in which, instead of partial side plates according to British Patent No. 545,859, there are used complete rotatable side discs as in British Patent No. 444,062, the arrangement is generally such that by reason of expense in operating gear only one of the said side discs is made retractable in order to allow the ball to be discharged from the machine. The considerable pressure which has been necessary to wind a firm ball results, however, in a tendency of the ball to adhere momentarily to the unopened disc, and therefore tends to lengthen unduly the undesirable dwell or non-winding period between the discharge of the ball and the initiation of a fresh ball. By the improvement according to the present invention, however, the advantages of using only partial side plates as described in British Patent No. 545,859 are combined with the added advantage of retracting not only one of the side plates as is usual in the disc machines of British Patent No. 444,062, but of retracting both the partial side plates, thereby completely freeing the ball, facilitating its discharge from the machine, and reducing to a minimum the undesirable dwell or non-winding period before the initiation of the fresh ball, it being also possible to increase the speed of the operating shaft and thereby the initiation of the fresh ball.

In the forms of the invention previously described, the partial side-plates 100, 100a are mounted for sliding movement on the eccentric guide-and-support rods 104, 104a and mention has been made of an improvement in their connection to the movable arm 36 of the driving pressure-roller, such improvement being simple and economical to make and lending itself particularly well to the retraction movements of the side plates in accordance with the previously referred to features of the invention.

The said improvement according to the present invention consists in dispensing with the pin and slot and lever assembly of British Patent No. 545,859 and providing a screwed-link pin 129,

129a for each side plate, one end of each of which link pins extends through an aperture 130, 130a on the upper lug 103, 103a of the corresponding side plate and the other end of which screws into a boss 131, 131a on the axial mounting of the driving pressure-roller 34 at the end of the pivoted arm 36. As shown more particularly in Figure 1, each link boss 131, 131a is slightly barrelled out in order to permit the retraction and return movements of the side plates by the eccentric rotation of their corresponding support-and-guide rods 104, 104a. On each screwed link pin 129, 129a, on either side of the lug 103, 103a of the corresponding side plate, are lock nuts or the equivalent 132, 132a. The distance between the two lock nuts is the same on each pin and determines the free movement which, for the reasons explained in detail in British Patent No. 545,859, the pins 129, 129a may be permitted in each direction of pivotal movement of the pressure-roller arm 36 towards and away from the balling centres 5 before the side plates 100, 100a partake of the said movement.

Figures 1 and 4 shows the relative positions of the parts when the partial side plates have just been returned from completing a ball into the position which they assume for the initiation and development of a fresh ball. The side plates have been returned longitudinally from the left to the right on the guide-and-support rods 104, 104a by the return pivotal movement of the driving pressure-roller arm 36 towards the balling centres, the distance between the two lock nuts on each link pin 129, 129a allowing the latter to move to the right by a corresponding amount with the pivoted arm 36 before the lock-nut on the left of the corresponding side plate lug 104, 104a engages with the said lug to move the plate to the right so that it then partakes of the return movement of the driving pressure-roller towards the balling centres. This helps to ensure that the side plates are opened before they start to be returned. From the positions shown in Figures 1 and 4, when the ball starts to build up, it gradually pushes the driving pressure-roller 34 away, but the side plates do not partake of a corresponding longitudinal movement on the guide-and-support rods 104, 104a until the link pins 129, 129a have first moved with the pressure-roller arm 36 to the left a distance sufficient to bring that lock nut 132, 132a thereon which is at the right-side of the corresponding side plate lug 103, 103a into engagement with the corresponding lug. This causes the plates thereafter to partake of the movement of the driving pressure-roller away from the axis of the balling centres 5 so that the side plates continue to shroud the nip of the driving pressure-roller with the ball as the diameter of the latter grows. This position wherein the side plates are partaking of the movement of the driving pressure-roller away from the balling axis is shown in Figure 5.

When the partial side plates have been so moved by the link pin connections 129, 129a, along the eccentric guide rods 104, 104a into their final limit positions corresponding to the full size of the ball being built, they are still firmly supporting the sides of the ball over a substantially large area extending from the nip with the driving pressure-roller to adjacent area at the top and bottom of the ball as shown in the drawings, whereupon the cam-shaft 41 operates automatically in the manner described

in British Patents Nos. 444,062 and 505,333 and the ball-release and side-plate-retraction control actions by the cams 20 take place as hereinbefore described.

5 It will be understood that although certain embodiments of the invention have been described by way of example and illustration only, the invention is not confined thereto and that many modifications of the same may be made within the scope of the appended claims.

I claim:

1. In a roll-forming or balling machine of the kind referred to, the combination of centre means on which a ball may be wound about a stationary axis, a driving pressure-roller mounted to be movable during balling away from said winding axis in order to accommodate the increasing diameter of the ball, partial side plates between which the ball is formed also mounted 10 to be movable during balling away from said winding axis in order to maintain effective support on the sides of the ball while keeping the nip with the driving pressure-roller shrouded during the whole of the balling period, and means 15 operable to retract bodily said partial side plates from the sides of the ball when in positions into which they have been moved in following up the nip of the ball with the driving pressure-roller, whereby to facilitate the discharge of the ball 20 from the machine, said partial side plates being thereafter returnable into their ball-confining positions for the initiation and development of a fresh ball.

2. In a roll-forming or balling machine of the kind referred to, the combination of centre means on which a ball may be wound about a stationary axis, a driving pressure-roller mounted to be movable during balling away from said winding axis in order to accommodate the increasing diameter of the ball, partial side plates between which the ball is formed also mounted 25 to be movable during balling away from said winding axis in order to maintain effective support on the sides of the ball while keeping the nip with the driving pressure-roller shrouded during the whole of the balling period, and means operable to retract bodily said partial side plates from the sides of the ball when in positions into which they have been moved in following up the nip of the ball with the driving pressure-roller, whereby to facilitate the discharge of the ball 30 from the machine, said partial side plates being thereafter returnable into their ball-confining positions for the initiation and development of a fresh ball.

3. In a roll-forming or balling machine of the kind referred to, the combination of centre means on which a ball may be wound about a stationary axis, ball-release-control means for retracting said centre means in order to allow 35 a ball to be discharged from the machine, a driving pressure-roller mounted to be movable during balling away from said winding axis in order to accommodate the increasing diameter of the ball, partial side plates between which the ball is formed also mounted to be movable 40 during balling away from said winding axis in order to maintain effective support on the sides of the ball while keeping the nip with the driving pressure-roller shrouded during the whole of the balling period, support-and-guide means 45 being mounted to be movable into and out of positions in which said partial side plates are respectively in their ball-confining and ball-non-confining positions, and means operable to effect a retraction of said side plate support-and-guide means, and thereby of the partial side plates themselves, into their ball-non-confining positions when a ball is to be discharged from the machine.

6. In a roll-forming or balling machine of the kind referred to, the combination of centre means on which a ball may be wound about a stationary axis, ball-release-control means for retracting said centre means in order to allow 50 a ball to be discharged from the machine, a driving pressure-roller mounted to be movable during balling away from said winding axis in order to accommodate the increasing diameter of the ball, partial side plates between which the ball is formed also mounted to be movable during balling away from said winding axis in order to maintain effective support on the sides of the ball while keeping the nip with the driving pressure-roller shrouded during the whole of the balling period, support-and-guide means 55 being mounted to be movable into and out of positions in which said partial side plates are respectively in their ball-confining and ball-non-confining positions, and means operable to effect a retraction of said side plate support-and-guide means, and thereby of the partial side plates themselves, into their ball-non-confining positions when a ball is to be discharged from the machine.

7. In a roll-forming or balling machine of the kind referred to, the combination of centre means on which a ball may be wound about a stationary axis, ball-release-control means for retracting said centre means in order to allow 60 a ball to be discharged from the machine, a driving pressure-roller mounted to be movable during balling away from said winding axis in order to accommodate the increasing diameter of the ball, partial side plates between which the ball is formed also mounted to be movable during balling away from said winding axis in order to maintain effective support on the sides of the ball while keeping the nip with the driving pressure-roller shrouded during the whole of the balling period, support-and-guide means 65 being mounted to be movable into and out of positions in which said partial side plates are respectively in their ball-confining and ball-non-confining positions, and means operable to effect a retraction of said side plate support-and-guide means, and thereby of the partial side plates themselves, into their ball-non-confining positions when a ball is to be discharged from the machine.

8. In a roll-forming or balling machine of the kind referred to, the combination of centre means on which a ball may be wound about a stationary axis, ball-release-control means for retracting said centre means in order to allow 70 a ball to be discharged from the machine, a driving pressure-roller mounted to be movable during balling away from said winding axis in order to accommodate the increasing diameter of the ball, partial side plates between which the ball is formed also mounted to be movable during balling away from said winding axis in order to maintain effective support on the sides of the ball while keeping the nip with the driving pressure-roller shrouded during the whole of the balling period, support-and-guide means 75 being mounted to be movable into and out of positions in which said partial side plates are respectively in their ball-confining and ball-non-confining positions, and means operable to effect a retraction of said side plate support-and-guide means, and thereby of the partial side plates themselves, into their ball-non-confining positions when a ball is to be discharged from the machine.

on which said partial side plates are mounted and guided in their movement of following up the nip of the ball with the driving pressure-roller, said support-and-guide means being mounted to be movable into and out of positions in which said partial side plates are respectively in their ball-confining and ball-non-confining positions, and means operable under the control of said ball-release-control means for effecting a retraction of said side plate support-and-guide means, and thereby of the partial side plates themselves, into their ball-non-confining positions when a ball is to be discharged from the machine.

4. In a roll-forming or balling machine of the kind referred to, the combination of centre means on which a ball may be wound about a stationary axis, a cam means and pivoted lever system for retracting said centre means in order to allow a ball to be discharged from the machine, a driving pressure-roller movable during balling away from said winding axis in order to accommodate the increasing diameter of the ball, partial side plates between which the ball is formed and which shroud substantially only the nip of the driving pressure-roller with the ball and part of the end surface and sides of the ball, said partial side plates being mounted to be movable during a part at least of the balling period in order to maintain effective support on the sides of the ball while keeping the nip with the driving pressure-roller shrouded during the whole of the balling period, and a side-plate-retraction means for retracting said partial side plates from the sides of the ball when it is desired to discharge the ball from the machine, said side-plate-retraction means being operable under the control of the same cam means as said pivoted lever system for said centre means.

5. In a roll-forming or balling machine of the kind referred to, the combination of centre means on which a ball may be wound about a stationary axis, a cam means and pivoted lever system for retracting said centre means in order to allow a ball to be discharged from the machine, a driving pressure-roller movable during balling away from said winding axis in order to accommodate the increasing diameter of the ball, partial side plates between which the ball is formed and which shroud substantially only the nip of the driving pressure-roller with the ball and part of the end surface and sides of the ball, said partial side plates being mounted to be movable during a part at least of the balling period in order to maintain effective support on the sides of the ball while keeping the nip with the driving pressure-roller shrouded during the whole of the balling period, and a side-plate-retraction means for retracting said partial side plates from the sides of the ball when it is desired to discharge the ball from the machine, said side-plate-retraction means being operable under the control of the same cam means as said pivoted lever system for said centre means and being movable in one direction by said cam means positively to retract said side plates from their ball-confining positions and being returnable by said cam means in the opposite direction positively to return said side plates into their ball-confining positions.

6. In a roll-forming or balling machine of the kind referred to, the combination of centre means on which a ball may be wound about a stationary

axis, a cam means and pivoted lever system for retracting said centre means in order to allow a ball to be discharged from the machine, a driving pressure-roller movable during balling away from said winding axis in order to accommodate the increasing diameter of the ball, partial side plates between which the ball is formed and which shroud substantially only the nip of the driving pressure-roller with the ball and part of the end surface and sides of the ball, said partial side plates being mounted to be movable during a part at least of the balling period in order to maintain effective support on the sides of the ball while keeping the nip with the driving pressure-roller shrouded during the whole of the balling period, and a side-plate-retraction means for retracting said partial side plates from the sides of the ball when it is desired to discharge the ball from the machine, said side-plate-retraction means being operable under the control of the same cam means as said pivoted lever system for said centre means and the control action as exercised by said cam means being from the same point on the cam and by means common to both said side plates and said centre means, whereby said side plates and centre means are adapted to be retracted from and to be returned again into their balling positions, all at the same time.

7. In a roll-forming or balling machine of the kind referred to, the combination of centre means on which a ball may be wound about a stationary axis, a cam means and pivoted lever system for retracting said centre means in order to allow a ball to be discharged from the machine, a driving pressure-roller movable during balling away from said winding axis in order to accommodate the increasing diameter of the ball, partial side plates between which the ball is formed and which shroud substantially only the nip of the driving pressure-roller with the ball and part of the end surface and sides of the ball, said partial side plates being mounted to be movable during a part at least of the balling period in order to maintain effective support on the sides of the ball while keeping the nip with the driving pressure-roller shrouded during the whole of the balling period, and a pivoted lever for retracting said partial side plates from the sides of the ball when it is desired to discharge the ball from the machine, said side-plate-retraction lever being operable under the control of the same cam means as said pivoted lever system for said centre means.

8. In a roll-forming or balling machine of the kind referred to, the combination of centre means on which a ball may be wound about a stationary axis, means for retracting said centre means in order to allow a ball to be discharged from the machine and for returning said centre means again into the balling position, a driving pressure-roller mounted to be movable during balling away from said winding axis in order to accommodate the increasing diameter of the ball, partial side plates between which the ball is formed also mounted to be movable during balling away from said winding axis in order to maintain effective support on the sides of the ball while keeping the nip with the driving pressure-roller shrouded during the whole of the balling period, normally stationary guide rods on which said partial side plates are mounted and guided in their movement of following up the nip of the ball with the driving pressure-roller, means whereby said guide rods are eccentrically mounted, and means for causing an

eccentric rotation of said guide rods in a direction to retract said partial side plates from their ball-confining positions when a ball is to be discharged from the machine and for causing a return eccentric rotation thereof into their normal positions for restoring said side plates into their ball-confining positions when the ball has been discharged from the machine.

9. In a roll-forming or balling machine of the kind referred to, the combination of centre means on which a ball may be wound about a stationary axis, means for retracting said centre means in order to allow a ball to be discharged from the machine and for returning said centre means again into the balling position, a driving pressure-roller mounted to be movable during balling away from said winding axis in order to accommodate the increasing diameter of the ball, partial side plates between which the ball is formed also mounted to be movable during balling away from said winding axis in order to maintain effective support on the sides of the ball while keeping the nip with the driving pressure-roller shrouded during the whole of the balling period, normally stationary guide rods on which said partial side plates are mounted and guided in their movement of following up the nip of the ball with the driving pressure-roller, means whereby said guide rods are eccentrically mounted so that an eccentric rotation thereof in respective directions causes a retraction of said partial side plates from their ball-confining positions and a return eccentric rotation thereof into their original positions restores said partial side plates to their ball-confining position, sprocket wheel means mounted on and individual to each of said guide rods, a flexible chain-like transmission passing round said sprocket wheel means and connecting the same in series in such a manner that by pulling on said chain-like transmission in one direction said sprocket wheel means are rotated to retract said side plates on their guide rods from their ball-confining positions and by pulling on said chain-like transmission in the opposite direction they are rotated to return said side plates into their ball-confining positions, and means operable to pull on said chain-like transmission.

10. In a roll-forming or balling machine of the kind referred to, the combination claimed in claim 9 wherein said means for pulling on said chain-like transmission comprises a pivoted lever.

11. In a roll-forming or balling machine of the kind referred to, the combination claimed in claim 9 wherein said means for pulling on said chain-like transmission comprises a side-plate-operating lever pivotally mounted intermediate its ends and to which the ends of said flexible chain-like transmission are connected on either side of the pivotal mounting of said lever, said chain-like transmission passing round said sprocket wheels and connected the same in series so that the guide rod means of one side plate is rotatably thereby in the opposite direction to the guide rod means of the other side plate, the arrangement being such that when said side-plate-operating lever is pivotally moved in one direction, one end thereof pulls on said chain-like transmission in a direction to rotate said sprocket wheels so that the guide rod means retract said side plates from their ball-confining positions, and when said lever is pivotally returned in the opposite direction the other end thereof pulls

back said chain-like transmission and rotates said sprocket wheels in the reverse directions in order to return said side plates into their ball-confining positions.

12. In a roll-forming or balling machine of the kind referred to, the combination of a pair of co-operating balling centres on which a ball may be wound about a stationary axis, a ball-release-control cam and pivoted lever for retracting each of said balling centres in order to allow the ball to be discharged from the machine, a driving pressure-roller movable during balling away from said winding axis in order to accommodate the increasing diameter of the ball, partial side plates between which the ball is formed and which shroud substantially only the nip of the driving pressure-roller with the ball and part of the end surface and sides of the ball, said partial side plates being mounted to be movable during a part at least of the balling period in order to maintain effective support on the sides of the ball while keeping the nip with the driving pressure-roller shrouded during the whole of the balling period, upper and lower pairs of normally stationary guide rods eccentrically mounted in the machine on which said partial side plates are mounted and guided in their movement of following up the nip of the ball with the driving pressure-roller, a sprocket wheel mounted on each of said guide rods, an extension on the end of one of said ball-release-control levers, a side plate operating lever pivotally mounted intermediate its ends and one end of which is secured to said extension on the end of said one ball-release-control lever so that when the latter undergoes pivotal movement it also imparts pivotal movement to said side plate operating lever, and a flexible chain-like transmission the two ends of which are connected to said side plate operating lever on either side of the pivotal mounting thereof and which passes round said sprocket wheels so as to connect all the latter in series in such a manner that in whichever direction said chain-like transmission is pulled it rotates the sprocket wheels of one side plate in one direction and the sprocket wheels of the other side plate in another direction, the arrangement being such that upon said cam-means pivoting said ball-release-control levers to retract said balling centres from one another, said side plate operating lever is pivotally moved by the extension on said one ball-release-control lever to pull said chain-like transmission in a direction such as to rotate said sprocket wheels to retract the side plates from their ball-confining positions, and when said ball-release-control levers are pivotally returned to close said balling centres against said extension on said one ball-release-control lever pivotally returns said side plate operating lever to its original position, thereby causing said lever positively to pull back said chain-like transmission and to rotate said sprocket wheels in the reverse directions to return said side plates into their ball-confining positions.
13. In a roll-forming or balling machine of the kind referred to, the combination claimed in claim 9 wherein said means for pulling on said chain-like transmission in a direction to retract said partial side plates from their ball-confining positions comprises a pivoted lever and separate means are provided for pulling said chain-like transmission back again in the opposite direction to return said partial side plates to their ball-confining positions.
14. In a roll-forming or balling machine of the

kind referred to, the combination claimed in in claim 9 wherein said means for pulling on said chain-like transmission comprises a side plate operating lever pivotally mounted towards one end thereof and connected at its other end to said chain-like transmission, said chain-like transmission passing round said sprocket wheels and connecting the latter in series in such a manner that in whichever direction said chain-like transmission is pulled said guide rod means of one side plate is rotated thereby in the opposite direction to the guide rod means of the other side plate, and an automatically operating restoring means associated with the guide rod on which is mounted the last of said sprocket wheels in the series and which yieldingly opposes any rotation of said sprocket wheels in directions resulting from movement of said side plate operating lever from its normal position corresponding to the ball-confining positions of said side plates.

15. In a roll-forming or balling machine of the kind referred to, the combination of a pair of co-operating balling centres on which a ball may be wound about a stationary axis, a ball-release-control cam and pivoted lever for retracting each of said balling centres in order to allow the ball to be discharged from the machine, a driving pressure-roller movable during balling away from said winding axis in order to accommodate the increasing diameter of the ball, partial side plates between which the ball is formed and which shroud substantially only the nip of the driving pressure-roller with the ball and part of the end surface and sides of the ball, said partial side plates being mounted to be movable during a part at least of the balling period in order to maintain effective support on the sides of the ball while keeping the nip with the driving pressure-roller shrouded during the whole of the balling period, upper and lower pairs of normally stationary guide rods eccentrically mounted in the machine on which said partial side plates are mounted and guided in their movement of following up the nip of the ball with the driving pressure roller, a sprocket wheel mounted on each of said guide rods, a side plate operating lever pivotally mounted towards one end thereof on the machine frame immediately below one of said ball-release-control cams, a camming stud on said lever engaging with a camming groove on said ball-release-control cam, a chain-like transmission connected to the non-pivoted end of said lever and which passes round said sprocket wheels so as to connect the latter in series in such a manner that in whichever direction said chain-like transmission is pulled the guide rod means of one side plate

is rotated thereby in the opposite direction to the guide rod means of the other side plate, and a counterweight means connected to that one of said guide rods on which is mounted the last of said 5 sprocket wheels in the series, the disposition of said chain-like transmission and the arrangement of the mechanism being such that upon said cam-means operating to retract said balling centres from one another, said side plate operating lever is pivoted by said cam-means in a direction which causes said chain-like transmission to rotate said sprocket wheels, and with them said eccentrically mounted guide rods, in directions to retract said side plates from their ball-confining positions, and 10 when said lever is returned again positively by said cam-means into its original position the slack of said chain-like transmission is taken up by said counterweight means rotating said last sprocket wheel and thereby all said sprocket wheels in their 15 respective reverse directions, thereby returning said side plates into their ball-confining positions.

16. In a roll-forming or balling machine of the kind referred to, the combination of centre means on which a ball may be wound about a stationary axis, a driving pressure-roller mounted on a pivoted arm so as to be movable during balling away from said winding axis in order to accommodate the increasing diameter of the ball, partial side plates between which the ball is formed 20 and which shroud substantially only the nip of the driving pressure-roller with the ball and part of the end surface and sides of the ball, support-and-guide means on which said partial side plates are mounted and guided and on which they are 25 movable during a part at least of the balling period in order to maintain effective support on the sides of the ball while keeping the nip with the driving pressure roller shrouded during the whole of the balling period, a screwed link-pin connecting each of said side plates to the pivoted 30 arm of said driving pressure roller for movement therewith, one end of each of said screwed link-pins being secured to said arm on the corresponding side of said driving pressure roller and the 35 other end slidably extending through an apertured lug on the corresponding side plate, and spaced abutment means provided on each of said 40 screwed pins on either side of said apertured lug of the corresponding side plate whereby to provide 45 a free distance of movement of said link-pins with the pressure-roller arm in either direction of the pivotal movement of the latter before a said abutment means on a link-pin engages with the lug of the corresponding side plate in order to move 50 the latter with the pressure-roller arm.

ADAM JOHNSTON STALKER.
